UNITED STATES PATENT OFFICE.

WORCESTER HADDOCK, OF CINCINNATI, OHIO, ASSIGNOR OF ONE-HALF TO
JACOB FRANK, OF SAME PLACE.

PROTECTING UNDERGROUND WIRES AND PIPES.

SPECIFICATION forming part of Letters Patent No. 351,913, dated November 2, 1886.

Application filed January 4, 1882. Serial No. 49,394. (No model.)

To all whom it may concern:

Be it known that I, WORCESTER HADDOCK, of the city of Cincinnati, in the county of Hamilton and State of Ohio, have invented certain new and useful Improvements in Means for Transmitting and Protecting Underground Wires and Pipes, of which the following is a specification.

The object of my invention is to provide means for transmitting and protecting electric wires and gas and water pipes underground in such a manner that they may be easily reached, and to provide means for retaining said wires and pipes in position.

Referring to the drawings forming part of this specification, Figure 1 is a transverse section across the main tube or covering and its accompaniments and showing the various wires and pipes in position. Fig. 2 is a sectional view representing one side of the tube or envelope and its accompaniments, the section being taken at the line $x-x$ of Fig. 1, and looking toward the side which is at the right hand in said figure. Figs. 3 and 4 are detail views showing the different forms of insulators which I employ. Fig. 5 is a plan view showing the manner of turning a corner, and also avoiding the catch-basins of the sewer at the street corner. Fig. 6 is a sectional elevation 30 of the arrangement shown in Fig. 5, looking toward the top of said figure, and also showing the method of crossing a street. Fig. 7 is a transverse section of the tube which leads toward the right hand of Fig. 6.

The outer covering or tube, X, is composed of the side plates, a, a', a^2, a^3, a^4 , the bottom plate, a^5 , and the top plate, a^6 , preferably made of iron. The meeting edges of these plates are provided with flanges b , through which bolts are passed to secure the various plates together. The side plates, a, a' , preferably extend perpendicularly downward from the curb A. The plate a^2 preferably extends perpendicularly downward for a short distance, and then obliquely downward toward the middle of the street. The plate a^4 preferably extends obliquely upward from the bottom plate, a^5 , to a point beneath the lower edge of the plate a^2 , and the plate a^3 extends perpendicularly between and 50 to the plates a^2 and a^4 . The plate a' prefera-

bly has an angle-plate, b' , which extends obliquely downward across an edge of said plate b' , being slightly removed from the plate a^5 , leaving an opening through which water may pass the bottom plate, a^5 , the edge of this plate resting on lugs b^2 , cast on the bottom plate, a^5 .

The top plate, a^6 , preferably extends across the top of the tube, one edge being provided with the flange c , which rests in a channel, c' , in the top edge of the plate a^2 , and the other edge resting on top of the plate a and against the curb A. Joists A' extend across the top of the tube, and are secured at either end to brackets B B' on the plates a and a^2 , and upon these joists rests the top plate, a^6 , the upper 65 surface of which is shaped to form the gutter to carry off the water from the street. A piece of rubber or other elastic material, b^3 , is interposed between the meeting ends of the various plates a^6 , (see Fig. 2,) to allow for expansion and contraction of said plates, and yet form a tight joint to prevent water from running into the tube to any considerable extent. This elastic piece is placed on one of the joists A', and is retained thereon between the upwardly-extending flanges b^4 on the joists. The bottom plate, a^5 , is made concave, and is provided at intervals with outlets A², through which any water which may run into the tube 70 is conveyed to the sewer. Within this tube so formed the electric wires and gas and water pipes are placed.

At intervals along the bottom of the tube are placed the brackets D, upon which the gas and water mains D' D² are laid. The brackets D are provided with shoes d, for preventing the brackets from tilting. One of these shoes rests in the angle formed at the junction of the side plate, a' , and the oblique plate b' , the other shoe, d , at the other end of the bracket 90 resting against the oblique side plate, a^4 . These brackets are not bolted to the tube X, as it is desirable that they should be longitudinally adjustable in the tube X to avoid the joints in the pipes. The shoes, however, hold the brackets in position and prevent them from tilting. The upper edges of these brackets are provided with notches, in which the pipes are laid. A foot, d' , is formed on the under side 95 of the bracket D, which foot rests upon the 100

ridge d^2 on the bottom plate, a^5 . d^3 d^4 represent branches of the mains $D'D^2$, these branches passing through the sides of the tube X.

Above the pipes and at one side of the tube X the electric wires are supported, as shown in Fig. 1. Upright posts E (see Figs. 1 and 2) are placed at intervals along the length of the tube, the upper ends of the posts being bolted to the under side of the joists A'. These posts, preferably, do not extend entirely to the bottom of the tube, but rest upon the upper end of oblique posts E', the lower ends of which latter posts are bolted to the oblique side plate, a^4 . The upper end of the post E' and the lower end of the post E are bolted together, as shown in Fig. 1, and an upright shoe or brace, E², extends from this joint down to the bottom of the tube, the lower end of this brace resting on the ridge d^2 on the bottom plate, a^5 . The advantage of this construction is that it allows either of the posts to be removed without materially interfering with the others. This is necessary to allow free access to the pipes or wires in cases of repairs or of putting in new lines of cable or wire. The electric wires traversing this tube must be insulated in any appropriate manner, and I have shown two methods of accomplishing this and of supporting the wires. In the upper part of the tube I have shown wires e, each one of which is insulated independently of the others, and below these wires I have shown several bundles of wires contained in common insulators e'—that is, several wires contained in one cable or general insulator, but preferably insulated from each other.

Extending from the side plates, a^3 a^4 , to the oblique post E' are the brackets F, one end of said brackets resting on lugs on the side plates and the other end resting against the oblique post E'. These brackets F may be bolted to the side plates and the post E', if desired, or the ends may be provided with flanges projecting from the sides of the brackets, which will prevent the brackets from turning. On these brackets F are laid the bundles e' of insulated wires, the brackets being preferably notched on their upper edges to receive said bundles.

Above the bundles e' are the bars e², extending from the side plates of the tube X to the post E. These bars in cross-section are shaped as shown in Fig. 3, and between these bars are placed the insulators e³, made of glass or other non-conducting substance. These insulators are preferably made in sections, so that the various wires may be placed in position without the necessity of drawing the entire wire through the insulator, as would be necessary were the insulators made in one piece.

Two forms of insulators are shown in Figs. 3 and 4, which may be employed. The one shown in Fig. 3 is provided with a number of teeth, e⁴, around which the wires are turned, as shown in the upper part of Fig. 3. This retains the wire in position, preventing it from slipping. The under side of these insulators

is provided with a notch, e⁵, which fits on the bar e², as shown in Fig. 3. A separate plate, e⁶, of glass or other non-conducting substance, 7c is placed on top of the teeth e⁴ after the wires have been placed in position, preventing them from becoming detached from the insulators.

Another form of insulator is shown in Fig. 4. This insulator is made in two halves, each 75 half being provided with a notch to fit on the bars e², and also with another notch, which, when the two halves are placed together, forms an opening, e⁷, through which the wires e pass. Each of these insulators may, if desired, be 80 provided with two openings, e⁷, as shown in the second row in Fig. 1. The object of this construction of the insulators is to permit the various wires to be stretched the entire length of the tube before being attached to the insulators. Wooden strips or bars h are bolted or otherwise attached to the various brackets and posts, around which the wires e are conducted and to which they are secured, to prevent them from coming in contact with any of the metal 85 in or belonging to the tube X, or with each other, as they are conducted from or into the tube.

The kind of insulated cables or wires and their mode of insulation and their precise location within the tube X may be varied as desired. Figs. 5 and 6 show the manner of conducting the tube around a catch-basin at the street corner and also of crossing a street. Fig. 5 shows a pipe, G, passing around the 90 catch-basin, and illustrating how it may be conducted in either direction. As the tube X crosses the street it is preferably lowered, as shown in Fig. 6, the purpose of this being to place the tube low enough to be out of the 95 way of street repairs. Another and important object of this lowering of the tube as it crosses the street is to permit underground cable railways to be constructed in the street without interfering with the tube. Where the tube X 100 crosses the street it may, if desired, be made double, as shown in Fig. 7.

When it is desired to inspect any of the wires or pipes in the tube, one of the top plates, a^6 , is lifted, when a man can descend into the 105 tube, and the space H being free from wires or pipes, he may go from one end of the tube to the other, if he so desires.

If preferred, cross pieces or joints I may be laid across the space H, one end resting on a 110 lug on the side plate and the other on the pipe D', and upon these joists a plank, J, may be laid, upon which the man may walk; but this plank may be left out and the man may then walk on the pipes.

What I claim as new and of my invention, and desire to secure by Letters Patent, is—

1. The tube composed of the bottom plate, a^5 , and having on one side the side plates, a^3 and a^4 , top plate, a^6 , and at the other side inclined plate a^2 , vertical plate a^3 , and inclined plate a^4 , substantially as and for the purposes set forth.

2. A tube provided at its upper portion at

one side with bracket B, and at the other side with plate a^2 , provided with bracket B', and having at its top the plate a^6 , extending from plate a to plate a^2 , and the joists or bars A', 5 supporting plate a^6 , and connected at one end to plate a and at the other end to plate a^2 , substantially as and for the purposes specified.

3. The combination of vertical side plate a , provided at its upper portion with brackets 10 B, side plate a^2 , provided with brackets B' and groove c' , and the top plate, a^6 , provided with flange c , engaging groove c' , and the supporting bars or joists A', extending beneath top plate, a^6 , from one side of the tube to the 15 other, substantially as and for the purposes set forth.

4. The combination of the tube X, constructed on one side with side plates, a^1 a^3 a^2 , and top, substantially as described, and with 20 inclined post E' and upright post E, substantially as and for the purposes specified.

5. The combination of the tube X, constructed on one side with side plates, a^1 a^3 a^2 , and top, substantially as described, and with 25 inclined post E' and upright posts E' and E, the post E' meeting said posts E' and E at the junction, substantially as and for the purposes specified.

6. The combination of the tube X, constructed on one side with plates a^1 a^3 a^2 , and having within it the upright posts E E', substantially as and for the purposes specified.

7. The tube provided with the bottom plate, a^5 , concave, as shown, and provided with the 35 ridge or flange b^2 , and the false bottom b' , resting at one side on the ridge b^2 and at the other supported by the other side of said bottom plate, substantially as and for the purposes specified.

40 8. The tube provided with the bottom plate or channel, a^5 , and provided with the ridge or flange b^2 , and the false bottom b' , resting at one side on the ridge b^2 and at the other side formed in one piece with the side or wall a' and supported by the adjacent side of the plate or channel a^5 , substantially as and for the purposes specified.

45 9. The tube X, having a concave bottom plate, a^5 , provided with outlet tubes or open-

ings A², and the false bottom extending across 50 over said bottom a^5 , substantially as and for the purposes specified.

10. The tube X, formed in sections whose line of union is substantially parallel to the length of the tube, and provided with the racks 55 extending part way across the tube and supported at one end by the outer wall and at the other end connected to interior supports, substantially as and for the purposes specified.

11. The combination of tube X and interior 60 support, E, and rack e^2 , supported at one end by the tube and at other end by support E, substantially as and for the purposes specified.

12. The combination of tube X and support E and rack F at one end supported on a lug 65 of support E' and at the other end on the lug of vertical side a^3 , and upright or side support, E, connected to the top or joists A', substantially as and for the purposes specified.

13. The tube X, constructed substantially 70 as described, in combination with the rack D, said rack being provided with the shoes d , and support d' , substantially as and for the purposes specified.

14. In a tube, the side plates, a a^2 , and the 75 joists A', connecting the upper portions of said plates, and gutter-plate a^6 , and elastic packing b^3 , placed between the adjacent ends of plates a^6 , substantially as and for the purposes specified.

80 15. The combination of the gutter-plates a^6 and the joist A', under side plates at and in the vicinity of their junction, and provided with flanges b^4 , and the packing b^3 , placed between the adjacent edges of said plates a^6 , and 85 joist A' and its flanges b^4 , upheld in position between and against said plates a^6 , substantially as and for the purposes specified.

16. The combination of the curb A and the gutter-plate a^6 , entering a notch in the face of 90 the curb and supported by the plates a a^2 of the tube X, substantially as and for the purposes set forth.

WORCESTER HADDOCK.
